UNITED STATES PATENT OFFICE

124,035

DESIGN FOR A GAME PIN

Abe P. Janssen, Nashua, Iowa

Application September 26, 1940, Serial No. 95,420

Term of patent 3½ years

To all whom it may concern:

Be it known that I, Abe P. Janssen, a citizen of the United States, residing at Nashua, in the county of Chickasaw and State of Iowa, have invented a new, original, and ornamental Design for a Game Pin, of which the following is a specification, reference being had to the accompanying drawing, forming part thereof.

I claim:

The ornamental design for a game pin, as shown.

ABE P. JANSSEN.
